ABSTRACT: A self-opening container constructed from a single-piece flat blank. A flower-petallike, self-opening end is produced by folding along cutouts and scoring lines on a flat blank. The self-opening end opens upon sliding an inner section longitudinally within an outer section, both produced by folding a unitary flat blank along score lines.

SINGLE-PIECE SELF-OPENING CONTAINER CONSTRUCTION

This invention relates to a new and improved single-piece container construction.

A primary object and advantage of the invention is the construction from a unitary flat blank of a self-opening container with a slidable inner section contained within an outer section.

A further object of the present invention is the provision of a self-opening petallike container end which automatically expands to expose the contents when a slidable inner section is manually moved toward the open end. The self-opening end also automatically closes upon itself when the inner section is slid manually away from the open end, thereby protecting the contents.

A further advantage of the present invention is the provision of a self-opening container which is both attractive and functional and may serve as a receptacle and container for any manner of goods. The goods are exposed upon longitudinal sliding of the inner section and concealed when the section is oppositely slid.

Other advantages of the present invention will become apparent upon reading the following specification and referring to the accompanying drawings in which similar characters of reference represent corresponding parts in each of the several views.

In the drawings:

FIG. 1 is a plan view of a flat blank for construction of a self opening container according to the present invention.

FIG. 2 is a perspective view of the blank partially folded over.

FIG. 3 is a perspective view of a completely constructed container in a fully closed position.

FIG. 4 is a perspective view of a fully constructed container in a half-open position.

FIG. 5 is a perspective view of a container in its fully opened and expanded position.

The container which is the subject of the present invention is constructed from a unitary flat blank II which is folded upon itself to form a fully constructed and self-opening container as shown in FIGS. 3-5. Blank II is preferably constructed of relatively thin cardboard or some other similar inexpensive material. It is understood that as this container may function as both a container and as a merchandising medium to promote the sale of goods, suitable advertising material and informative matter may be printed or otherwise presented on the exposed surfaces of the container. Coloring various sections in different shades enhances the expanding flower petal concept which is one of the attractive features of the invention.

Constituting the largest flat portions of blank II are longitudinal panels 13, 15, 17 and 19, which are adjacent one another, and longitudinal outer panels 21, 23, 25 and 27, which are adjacent one another at the opposite end of blank II, as shown in FIG. 1. Defining panels 13 to 19 are longitudinally extending fold lines 29, 31, 33 and 35, which are formed in blank II to facilitate folding along said fold lines. Said fold lines extend longitudinally the full length of blank II and also delineate inner panels 21 to 27, in which portion said fold lines are identified as 37, 39, 41 and 43. Panels 13, 15, 17 and 19, upon complete construction, will form the sides of an outer section, generally designated 45. Correspondingly, panels 21, 23, 25 and 27, upon completion of construction, will form the sides of an inner section, generally designated as 47. The interrelationship of outer section 45 and inner section 47 will become apparent in referring to the following specification.

Adjacent panel 13 and separated therefrom by fold line 29, is glue flap 49. Similarly, adjacent a panel 21 and separated therefrom by fold line 37 is glue flap 51. Cut into the end of panel 13 is arc-shaped cutout 53, likewise arc-shaped cutout 55 is cut into the lower end of panel 17.

Forming the bottom end of inner section 47 are end-flaps 57, 59, 61 and 63. End flap 57 and end flap 61 are separated from sections 21 and 23, respectively, by fold line 65. In a like

manner, flap 63 is divided from section 27 by fold line 65, which extends across the width of blank II as best shown in FIG. 1. Fold line 67 separates end-flap 57 from tuck-in flap 59. End-flap sections 57 and 61 are defined by slit 69, which extends from the end of flap 61 to score line 65 as an extension of fold line 39.

That part of blank II which forms the self-opening end of the container when fully assembled, comprises four sections generally designated 71, 73, 75 and 77. Separating end section 71 from 73, 73 from 75, and 75 from 77 are, respectively, cutouts 79, 81 and 83, each of which form a quadrilateral shape as shown. Quadrilateral cutouts 79, 81 and 83 are each symmetrical about a line forming a continuation of respectively, score lines 31-39; and 33-41; and 35-43. The outwardly facing edge of section 71 designated panel 85, is indented in a like manner as one side of the quadrilaterals 79, 81 and 83. The outwardly facing edge 87 of section 77 is a straight line and a continuation of the outer edges of panels 19, 27 and 63. Extending laterally across blank II and connecting the common obtuse angles of quadrilateral cutouts 79, 81 and 83, is fold line 89. Extending laterally across blank II is fold line 91 which delineates the demarcation between panels 13 and 71; 15 and 73; 17 and 75; and 19 and 77. Similarly, extending laterally across blank II is fold line 93, which delineates the demarcation between panels 21 and 71; 23 and 73; 25 and 75; and 27 and 77. Extending laterally across blank II is fold line 95 which is parallel to and immediate between, fold lines 89 and 93, as shown. Extending diagonally across each of panels 71, 73, 75 and 77 are fold lines 97 and 99. To simplify description, the position of fold lines 97 and 99 will be described only with reference to panel 71, it being understood that they are identically placed in panels 73, 75 and 77. Fold line 99 extends diagonally across panel 71 from the intersection of the edge of flap 49, fold line 29 and fold line 91, thence to the opposite edge of panel 71 at cutout 79 to intersect with fold line 95. Similarly, fold line 97 extends diagonally from the intersection of fold line 95 at edge 71 to the apex of cutout 79 at the intersection of fold line 31, and fold line 91. Fold lines 99, 97 and 89 meet at a common intersection points 101 on the surface of end area 71. For purposes of identification, the various areas of end panel 71 are identified as follows: Between fold line 95 and 93, area 103; the triangle formed by fold lines 95, 97 and 99 is area 91; the corresponding triangle 107 is formed by fold lines 91, 99 and 97; the smaller triangles 109 and 111 are formed respectively by edge 85 and fold lines 99 and 89, and by fold lines 89, 97 and edge 85; corresponding small triangles 113 and 115 are formed, respectively, by fold lines 97, 89 and cutout 79, and fold lines 89, 99 and cutout 79. For purposes of simplicity in description, it is understood that only end opening surface 71 is completely identified as to the various surfaces formed by fold lines and cutouts, it being understood that identical surface areas are formed respectively in panels 73, 75 and 77, in which cases, triangular panes panels 103, 105, 107, 109, 111, 113 and 115 are designated by the addition of the letters a, b and c, respectively. This is with the exception of area 77, in which straight line edge 87 forms the outer edge thereof.

Proceeding now to a description of the method of folding and constructing a completed container: Preliminarily, as 73, 75 in FIG. 1, each fold line 89 is folded 103, 105, 107, 109, 111, 113 upwardly and each fold line 97 and 99 is folded downwardly, points 101 becoming apices and the backs of triangles 109, 111, 113 and 115 are in contact. Referring to FIG. 2, it is seen that portions designated generally as outer section 45 are folded upwards away from the flat surface of blank II to overlap section 47. In the intermediate construction stage shown in FIG. 2, outer panels 45 are approximately parallel to and a slight distance above, inner panels 47. At this stage of construction it is seen that panel 13 is immediately above panel 21, 15 above 23, 17 above 25, and 19 above 27. It is at this point that blank II is folded about itself along fold lines 29, 37, and 31, 39 and 33 and 41, and 35 and 43 to form two boxlike enclosures. Thus, flap 51 is attached to the inner sur-

face of panel 27 with a suitable adhesive material, the method of which is well-known in the art, to form inner section 47. In a similar manner, flap 49 is attached to the inner surface of panel 19 with adhesive material to form outer box section 45. The bottom of inner box structure 47 is closed by folding flaps 5 61 and 63 upon each other and by closing flap 57 thereupon, inserting flap 59 immediately adjacent panel 25, as is well-known in the art to form a box closure without the need for adhesives.

With inner section 47 pulled downwards to its full extent 10 within outer section 45, a closed box structure is presented as shown in FIG. 3. The upper end of outer section 45 is closed by the four triangle-shaped panels 107a—c closing upon and adjacent to one another. The method in which outer section 45 automatically opens and closes upon itself in a flower petal-like manner is now described. It is apparent that the folding process has produced two box sections slideable about one another. That is, outer section 45 is slideable longitudinally about inner section 47 as shown, with fold lines 91, 95 and 93 functioning as hinges. As inner section is manually pushed 15 partially upwardly within outer section 45, the petal-like shaped end panels 71, 73, 75 and 77 expand upwardly and outwardly until an intermediate position shown in FIG. 4 is produced. At this stage, triangular-shaped panels 105a—c, become parallel to bottom 51 of inner section 47 and are at 20 right angles to inner box wall surfaces 21, 23, 25 and 27. As inner section 47 is further manually pushed upward (sliding within outer section 45) the opening assembly 71, 73, 75 and 77 open fully outwards as shown in FIG. 5. In the fully open 25 position of FIG. 5, surfaces 103a—c are fully exposed and are parallel to bottom 51 and therefore at right angles to side surfaces 13, 15, 17 and 19 of outer box section 45. In this position inner section 47 is substantially entirely contained within outer section 45. Thumb and finger cutouts 53 and 55 are 30 used to retract section 47.

At this point, with the container fully open, the interior of inner section 47 is fully exposed and the contents thereof are available for easy access. At this point the user may put in or take out whatever goods are contained within inner section 47, as delineated by inner panels 21, 23, 25 and 27. 35 Thereafter, the process may be reversed by inserting a thumb and forefinger in cutouts 53 and 55 on inner panels 21 and 25 and pulling downwardly, which reverses the process, closing the box until the fully closed position shown in FIG. 3 is obtained.

The result is a unitary container construction which is easily and inexpensively manufactured and when folded in upon itself produces a sliding self-opening container which quickly and easily exposes the contents and upon closing produces a fully closed protective container for any manner of goods. By 40 printing the exposed panels in different colors, the folding and unfolding steps exposes different colors at different times and produces a very pleasing effect. A container constructed according to the present invention may be made not only in the square cross-sectional area herein described, but may be made with a cross-sectional area octagonal, hexagonal, etc. with only slight modifications of the example herein described, as 45 will readily occur to one skilled in this art.

It is understood that this invention has been described with reference to the example for purposes of clarity of understanding and that certain changes may be practiced within the scope of this invention and of the appended claims.

I claim:

1. A flat blank for a self-opening container comprising: a plurality of first panels foldable about each other to form 55

an outer section; a plurality of second panels foldable about each other to form an inner section contained within and slideable within said outer section; a plurality of closure panels intermediate said first panels and said second panels, said closure panels forming a closed end for the common opening of said inner and outer sections; a said plurality of first panels comprising a first set of four rectangular outer wall panels; said plurality of second panels comprising a second set of four rectangular inner wall panels at the opposite end of said blank from said first set; said plurality of closure panels comprising a set of four foldable panels, each of said last-named panels having each end common to one end of a wall panel of said first and second set of wall panels, said foldable panels separated from each other by a quadrilateral opening in said blank; each of said four foldable closure panels comprising a first closure panel with a first end common to one end of said first panels; a second closure panel formed of a plurality of triangular-shaped panels delineated by fold lines, said first closure panel and said second closure panel having a common edge delineated by a fold line; and in which said plurality of triangular-shaped panels further comprises:

a first triangular section with its base common to said common edge between said first and second closure panels; a second triangular panel with its apex common to the apex of said first triangular panel and having its base parallel to the base of said first triangular panel; third and fourth triangular panels adjacent first edges of said first and second triangular panels; and fifth and sixth triangular panels adjacent second edges of said first and second triangular sections, opposite said first edges.

2. A self-opening container comprising:

an inner section; an outer section, said inner section longitudinally slideable within said outer section, end closure means common to said inner and outer sections, said end closure means opening upon the full insertion of said inner section within said outer section and closing upon the partial removal of said inner section from said outer section; a plurality of foldable portions adjacent the walls of said inner and outer sections, said foldable portions folding in to cover the opening of said sections when said inner section is partially removed from said outer section; a first panel adjacent a wall of said inner section, said first panel being at substantially a right angle to said wall when said closure means are fully open, and parallel to said wall when said means are fully closed; a second panel adjacent a wall of said outer section, said second panel being at substantially a right angle to said outer wall when said closure means are fully closed and forming a portion of the closure of said opening; and closure connection means connecting said first panel with said second panel whereby said closure means opens upon full insertion of said inner section within said outer section.
